UNITED STATES PATENT OFFICE.

ROSA JOEL, OF NEW YORK, N. Y.

WASHING-MACHINE.

SPECIFICATION forming part of Letters Patent No. 404,545, dated June 4, 1889.

Application filed January 26, 1889. Serial No. 297,598. (No model.)

To all whom it may concern:

Be it known that I, ROSA JOEL, of the city, county, and State of New York, have invented certain new and useful Improvements in 5 Washing-Machines, of which the following is a specification.

This invention relates to an improved washing-machine which can be used in connection with the ordinary stationary wash-tubs, said 10 washing-machine being either permanently or removably applied to the wash-tub, as desired; and the invention consists of a washing-machine the frame of which is secured to the top of the wash-tub and provided with 15 bearings for a crank-shaft, having downwardly-extending arms which carry a rubbing-roller, that is oscillated by a handle attached at the outer end of the crank-shaft. The oscillating roller is provided with caps at the 20 ends having threaded rods, which are screwed into tubular interiorly-threaded arms of the crank-shaft, so that the roller can be adjusted higher or lower, according to the depth of the wash-tub with which the rubbing-roller is 25 used.

In the accompanying drawings, Figure 1 represents a perspective view of my improved washing-machine, shown as applied to a stationary wash-tub. Fig. 2 is a vertical trans- 30 verse section of the wash-tub having the washing-machine in side elevation. Fig. 3 is a detail vertical section of one of the end caps of the rubbing-roller, showing the connection of the same with one of the tubular arms of the 35 crank-shaft.

Similar letters of reference indicate corresponding parts.

Referring to the drawings, A represents a stationary wash-tub of the usual construction, 40 to the top of which is applied either permanently or detachably a frame B, which is lined at its inner side with a layer of sheet metal a, that extends below the bottom edge of the frame B over the inner edge of the tub, so as 45 to prevent thereby the water from passing over the edges of the tub. To the outside of the frame B are applied fixed lugs or ears b, which retain the frame firmly in position on the wash-tub, and which may be screwed or 50 otherwise attached to the wash-tub when the washing-machine is to be permanently attached to the same. The lid of the wash-

tub may be hinged to the top of the frame B if the same is permanently attached to the tub. It is preferable to attach the washing-machine permanently to the tub, which is of special advantage when two or more tubs are arranged sidewise of each other. The frame B is provided at one side with a plate d, carrying a bearing-pin d', and at the 55 opposite side with a bearing e, set into a recess of the frame. The fixed pin d' and the recess e support a crank-shaft C, to the lower ends of the arms C' of which is applied a rubbing-roller D. One end of the crank-shaft 60 is bent forward beyond the front wall of the wash-tub A and then upward and provided with a handle E, parallel to the axis of the crank-shaft C and roller D. By oscillating the handle E the roller D is oscillated to and fro in the tub, so as to exert a rubbing action on the clothes in the same. The rubbing-roller D forms a part of the crank-shaft C, and is attached to the tubular and interiorly-threaded arms C' of the same by screw- 65 rods f' of caps f, attached to the ends of the roller D. One of the crank-arms C' is made integral with the shaft C, while the opposite arm C' is provided with a sleeve f² at the upper end, which is hung to the pin d', that 70 forms the bearing for the rear end of the crank-shaft. The rubbing-roller D can be adjusted higher or lower by the screw-rods of the end caps, which is accomplished before 75 the caps are finally attached to the roller. The roller D is made of wood or other suitable material and inserted into the caps, after 80 the same have been adjusted to the proper depth, and then fastened to the caps. The rubbing-roller is then in position for washing, 85 which is accomplished by oscillating the roller by means of the handle, so that the clothes in the wash-tub are moved from one side to the other in the same, and thereby quickly and effectively washed by the rubbing action 90 of the roller on the clothes.

The washing-machine can be furnished at a comparatively low price and can be quickly applied to the tubs, so as to form a convenient and effective attachment for the same.

Having thus described my invention, I claim as new and desire to secure by Letters Patent—

1. The combination, with a stationary wash-tub, of a supporting-frame secured to the top

of the same, a crank-shaft supported in bearings of said frame, a handle at the outer end of the crank-shaft, and a rubbing-roller at the lower part of the crank-shaft, substantially as set forth.

2. The combination, with a stationary wash-tub, of a supporting-frame secured to said tub, a crank-shaft supported in bearings of the frame and provided with tubular internally-threaded crank-arms, a handle at the outer upwardly-bent end of the crank-shaft, a rubbing-roller, and caps attached to the ends of the roller and provided with screw-rods for engaging the tubular crank-arms, substantially as set forth.

3. The combination, with an oscillating crank-shaft supported in suitable bearings and provided with tubular internally-threaded crank-arms, of a rubbing-roller and end caps attached to said roller and provided with screw-rods that engage the crank-arms, so as to adjust the roller higher or lower on the crank-arms, substantially as set forth.

In testimony that I claim the foregoing as my invention I have signed my name in presence of two subscribing witnesses.

ROSA JOEL.
